US00D840430S

(12) **United States Design Patent** (10) **Patent No.:** **US D840,430 S**
Elatta (45) **Date of Patent:** **** Feb. 12, 2019**

(54) **DISPLAY SCREEN OR PORTION THEREOF WITH ICON**(71) Applicant: **Agile Transformation, Inc.**, Omaha, NE (US)(72) Inventor: **Sally Elatta**, Omaha, NE (US)(73) Assignee: **Agile Transformation, Inc.**, Omaha, NE (US)(***) Term: **15 Years**(21) Appl. No.: **29/647,492**(22) Filed: **May 14, 2018****Related U.S. Application Data**

(63) Continuation of application No. 29/578,990, filed on Sep. 27, 2016, now Pat. No. Des. 818,001.
